UNITED STATES PATENT OFFICE.

MICHAEL FEELY, OF PROVIDENCE, RHODE ISLAND.

DESIGN FOR A BADGE.

Specification forming part of Design No. 5,777, dated April 16, 1872.

To all whom it may concern:

Be it known that I, MICHAEL FEELY, of the city and county of Providence, State of Rhode Island, have invented a new and original Design for Badge, of which the following is a specification:

My invention consists of a combination of figures representing a cross, sunburst, and two sprigs of shamrock stamped, engraved, and enameled on gold, silver, or other metal, quarter-foil in shape, surmounted by an arch, upon which are the letters and word C. T. A. U. of A., whereby a new and distinctive badge is obtained.

The nature of my invention is fully represented in the accompanying drawing, to which reference is made.

Figure 1 is a view of the face of a badge embodying my invention. Fig. 2 is a side view of the same, showing the attaching-pin.

a a represents a cross surrounded by a sunburst; b b, two sprigs of shamrock, which I inlay with green enamel; c c, an arch, with the letters and word C. T. A. U. of A.

What I claim as my invention is—

A design for badge, as herein set forth.
MICHAEL FEELY.
